(57) **CLAIM**

The ornamental design for a cutting board holder as shown and described.

DESCRIPTION

FIG. 1 is a front perspective view of a cutting board holder showing the new design;

FIG. 2 is a front elevation view thereof;

FIG. 3 is a right side elevation view thereof, the left side being the same;

FIG. 4 is a rear elevation view thereof;

FIG. 5 is a top plan view thereof; and,

FIG. 6 is a bottom plan view thereof.

The broken lines of the drawings depict non-claimed portions of the cutting board holder and form no part of the claimed design.

1 Claim, 6 Drawing Sheets
